UNITED STATES PATENT OFFICE.

IVAR F. WARME, OF SYRACUSE, NEW YORK, AND JOHN C. TALIAFERRO, OF BALTIMORE, MARYLAND, ASSIGNEES TO CONTINENTAL CAN COMPANY, INCORPORATED, OF SYRACUSE, NEW YORK, A CORPORATION OF NEW JERSEY.

FILLED-CAN-CLOSING APPARATUS.

1,270,078.

Specification of Letters Patent. Patented June 18, 1918.

Application filed July 27, 1914. Serial No. 853,559.

To all whom it may concern:

Be it known that we, IVAR F. WARME and JOHN C. TALIAFERRO, citizens of the United States, residing at (1) Syracuse, in the 5 county of Onondaga, State of New York, and (2) Baltimore, Maryland, respectively, have invented certain new and useful Improvements in Filled-Can-Closing Apparatus, of which the following is a description, reference being had to the accompanying drawing and to the figures of reference marked thereon.

The invention relates to new and useful improvements in can closing apparatus and 15 more particularly to an apparatus wherein a plurality of closing machines are automatically supplied with filled cans to be closed.

An object of the invention is to provide a 20 filled can closing apparatus of the above character wherein a rotating cylinder having a thread wound thereon may be utilized for conveying the filled cans and for delivering the cans to any one or all of a series 25 or gang of closing machines.

A further object of the invention is to provide an apparatus of the above character in which the rotating cylinder is so constructed as to operate in conjunction 30 with an intermittently operated gate for forcing a certain number of filled cans on to the receiving table of a closing machine.

A still further object of the invention is to provide means whereby a positively rotated 35 table may be utilized for delivering filled cans in spaced relation on to a rotating conveyer, having a thread or threads wound thereon for engaging and moving the filled cans along a supporting rail.

40 A still further object of the invention is to provide an apparatus of the above character with a receiving carrier on to which the closed cans are discharged, which receiving carrier delivers all of the closed cans 45 to a common point where they may be taken by other conveyers, or otherwise disposed of.

These and other objects will in part be obvious and will in part be hereinafter more fully disclosed.

50 In the drawings which show by way of illustration one embodiment of the invention,

Figure 1 is a plan view showing more or

less diagrammatically, and partly in section, an apparatus embodying our improvements.

Fig. 2 is a view partly in side elevation and partly in section of the same.

Fig. 3 is an end view partly in section and partly in end elevation of the same.

Fig. 4 is an enlarged plan view, showing a portion of the receiving end of the machine.

Fig. 5 is an enlarged side elevation of the same;

Fig. 6 is a detail in side elevation, showing the driving pulley and friction clutch therefor.

Fig. 7 is an enlarged detail, showing in full lines the gate retracted, and a filled can passing through the opening therefor, and in dotted lines the gate closed and the can forced along.

Fig. 8 is a transverse sectional view, through the supporting frame and feed cylinder.

Fig. 9 is a detail showing in plan the operation of the separating plate.

Fig. 10 is a view showing a modified form of the invention.

The invention consists generally in providing a supporting frame in which is mounted a rotating cylinder. This cylinder has a thread or threads spirally wound thereon, which thread operates to convey the cans along a supporting ledge placed one side of the frame, that is to say, the filled cans rest partly on the cylinder and partly on the supporting ledge and are slid along the ledge as the cylinder rotates. The cans are placed on a receiving table at the receiving end of the conveyer in any suitable way, preferably by the conveyer which delivers the same from the filling machine directly on to this receiving table. The receiving table is positively rotated and operates in conjunction with a spacer to deliver the cans in spaced relation on the rotating cylinder, that is to say, there is one can placed between the adjacent threads on the cylinder.

This supporting ledge for the cans also has a side rail against which the cans are forced by the action of the spirally wound thread on the cylinder. This side rail is cut away adjacent the receiving table of the

first closing machine and a sliding gate is adapted to close this cut away portion or open the same so that a can may be forced through the opening on to the receiving table. The gate is reciprocated in proper timing to the travel of the cans so that the rotating cylinder will deliver a predetermined number of cans on to this first receiving table. If the apparatus is designed 5 to work in conjunction with two closing machines, then it is desirable that the gate shall open so as to receive every other can, provided the conveyer is fully supplied with cans. From the receiving table, the cans 10 are conveyed in the well known way to the closing machine. The cans not taken from the conveyer at the first machine are conveyed along and if more than two machines are used, then another opening may be provided 15 in the side rail and a second sliding gate used to control the same. The remaining filled cans on the conveyer would then be delivered to a third machine. Means is also provided for closing the openings even 20 when the gate is reciprocated so that any one of the machines may be put out of operation, if desired.

After the cans have been closed, they are delivered on to a traveling conveyer which 25 runs underneath the cylinder and this traveling conveyer brings the closed cans of all the machines to a common point where they may be delivered on to other conveyers, or otherwise disposed of.

Referring more in detail to the drawings, our improved closing apparatus consists of a supporting frame which, as herein shown, includes a front supporting bracket 1, a middle bracket 2, and an end bracket 3^a. These 30 brackets are the legs of the supporting frame. Extending from the supporting legs or bracket 1 to the central bracket 2 are side frames 3 and 4. These side frames are bolted to the brackets in any suitable way and each consists of a vertical member 5 and a horizontal member 6. The horizontal members 6 are spaced from each other. Mounted in the brackets 1 and 2 is a rotating conveyer 7. This conveyer is in the form of a 35 cylinder and has a spirally wound thread thereon. The cylinder is preferably hollow so that it may be light in weight, and said hollow cylinder is provided with a cap 9 carrying a projecting sleeve 10 which forms a bearing for one end of the cylinder, while the other end of the cylinder is provided with a similar cap having a sleeve 11 attached thereto. This sleeve has a bearing in the bracket 1. The cylinder is so positioned 40 that the thread thereof projects slightly above the horizontal members 6 of the side frames so that a filled can may rest on one of the horizontal members of the side frame which becomes a supporting ledge therefor, 45 and on the cylinder itself. It will be ob-

vious from Fig. 1 of the drawings that when the cylinder is rotating in the direction of the arrow thereon that the thread will tend to force the can bodies toward the left hand side frames viewing the cylinder in the direction of travel of the cans.

A side rail 12 is bolted to the side frame 3 so that it can be adjusted transversely of the frame. This side rail is set back from the edge of the horizontal member 6 so as to 5 leave a supporting ledge for the filled cans, as above referred to.

At the receiving end of the cylinder there is a rotating disk or receiving table 13. A bracket 14, shown in dotted lines in Fig. 4, 80 is bolted to the end bracket 1, and this disk is mounted to rotate in this bracket 14. The disk 13 overlaps the end bracket 1 and its extreme edge is substantially in line with the end of the cylinder. This disk is rotated 85 in the direction of the arrow indicated in Fig. 1. A guide rail 15 has a supporting shank 16 which is clamped to the side frame 3. This shank is slotted at 17 and bolts 18 passing through the slots secure the rail to 90 its support so that it may be adjusted transversely of the cylinder. The rail 15 is in the form of a loop and the outer end extending over the disk is substantially concentric with the disk. This concentric portion leads 95 into a straight portion 19 which directs the filled cans on the disk toward the outer edge of the disk and off from the disk on to the drum. As the disk rotates the filled cans resting thereon will be brought into contact with this 100 guiding rail and the face 19 thereof will accomplish the result stated. A second guide rail 20 is pivoted at 21 to the bracket 14 and at its outer end is adjustably attached to the horizontal member 6 of the side frame 105 4. The outer end of this rail is slotted as at 21 and bolts 22 hold the same in adjusted positions. This guide rail 20 is formed with a recess 23 in which is pivoted a separating plate 24. Said plate is pivoted at 25 and projects at each side of the pivot. A spring 110 normally holds this plate so that the forward end thereof is housed in the recess or cut away part of the guiding rail 20. This permits a can to pass by the end of the plate. This plate is so shaped that as the can is passing by the other end thereof, it will swing the plate bringing the end 25 out of the recess and holding back the cans on the disk until the can which is passing the plate is carried past the outer end thereof, after which the spring returns the plate to normal position allowing another can to pass. The purpose of this separating plate is to 115 so space the filled cans that there will only be one can between adjacent threads on the drum.

As shown in Fig. 1 of the drawings, we have provided a filled can closing apparatus 120 wherein there are only two closing machines, 125

indicated diagrammatically at A and B, respectively. The guide rail 12 is in the form of a horizontal plate and is mounted on spacing collars 26 so that this rail is slightly raised above the supporting ledge. The rail terminates at 27 forming a space 28 which is directly opposite a receiving disk 29 of the closing machine A. This receiving disk overlaps the horizontal member 6 of the side frame and this horizontal member is recessed at 30 to receive the disk so that the upper face of the disk is substantially flush with the upper face of this side frame which is also the supporting ledge for the filled cans. This opening indicated at 28 is controlled by a reciprocating gate 31. The gate 31 is mounted on an angle plate 32 which is secured by screws 33 to a reciprocating bar 34. The bar 34 lies flat against the vertical member of the side frame 3 and is guided by a suitable bracket 36. The gate 31 is attached to the angle plate 32 by bolts 37. The inner face of the gate is in line with the inner face of the guide rail 12. The outer face of the gate adjacent its free end is tapered as at 38, see Fig. 1.

When the gate 31 is moved to the position shown in full lines in Fig. 4, the opening 28 is closed and a can conveyed along by the cylinder will be carried by the opening 28. If, however, the gate is open, then when a can reaches the opening 28 the thread on the cylinder forces the can over on to the receiving disk 29. As the gate is closing it will, through the tapered face thereof, assist in crowding the cans well on to the rotating disk. It will be apparent that if the gate is properly timed every other can may be taken from the rotating cylinder on to the receiving disk of the closing machine A. This gate, however, may be closed to take every third can, or every fourth can, just as desired.

The filled cans which pass by the opening 28 will be conveyed along the supporting ledge and, as shown in the drawings, delivered to the closing machine B. The closing machine B is provided with a rotating receiving disk 39 which overlaps the end bracket and side supporting frame which are recessed, as at 40, so that the upper face of this disk is substantially flush with the upper face of the side frame. The rail 12 is cut away or tapered, as at 41. The threads on the cylinder force the filled cans on to the receiving disk 39. A guiding rail 42 is pivoted at 43 and overlaps the disk 39 and in effect forms a continuation of the guiding rail 42 of the closing machine B. As the disk rotates the filled cans will be carried along these rails 42 and delivered to the closing machine. This guiding rail 42 is similar to the guiding rail 44 of the closing machine A.

65 The various parts above referred to are

operated from the driving shaft 45. This driving shaft is journaled in suitable bearings in the bracket 1. Fixed to the shaft at the outer end thereof is a hub 46 having outwardly extending radial arms 47 which support a flexible gripping member 48. Loosely mounted on the shaft is a sleeve carrying a belt wheel 49. The flexible member 48 is located within this belt wheel and when expanded or forced outwardly is adapted to grip the belt wheel and lock the belt wheel to the driving shaft 45.

Pivoted on the radial arm 47 is a swinging lever 50. This lever is pivoted at 51. A lug 52 projecting from the lever engages the end of the flexible member 48 at 53. The other end of this lever carries a sleeve 54 in which is a bolt 55 having a rounded head 56 adapted to engage the cone surface 57 of a sleeve 60 which is splined to and slidable upon the projecting end of the main shaft. When this sleeve is moved to the right, as viewed in Fig. 2, the arm 52 to press against the end of the flexible member expanding the same and causing said flexible member to grip the inner face 61 of the driving pulley 49. This cone shaped sleeve is moved back and forth on this shaft by a forked arm 62. This forked arm is carried by a rod 63 which slides in bearings carried by the cover plate for the gears. Said rod is moved back and forth by a hand lever 64 which is connected to the rod and pivoted at 65 to said plate. When the sleeve is moved in the opposite direction, the yielding member 48 will be released from the driving pulley.

The main shaft 45 carries a gear wheel 66 which meshes with a gear wheel 67 which in turn meshes with a gear wheel 68 mounted on a shaft 69. The gear wheel 68 has a laterally extending flange 70 which is cut so as to form a cam for operating the sliding gate 31. The sliding gate 31 is attached to a bar 34, as above described. This bar carries a roller 71 which engages the upper forked end 72 of the lever 73 pivoted at 74 to a supporting frame of the machine. Said lever between its ends carries a roller 75 which bears against the cam 70 formed on the gear wheel 68. A spring 76 is attached at one end of the lever 73 and at its other end to a fixed bracket 77 carried by the side frame of the machine. This spring normally holds the roller in contact with the cam 70. The cam is so shaped that as the gear wheel 68 is rotated the bar 34 will be reciprocated back and forth.

A second gear wheel 78 is rigidly attached to the gear wheel 68 and this gear wheel 78 meshes with a gear wheel 79 mounted on the sleeve 11 at the receiving end of the drum so that the rotation of the main shaft will be imparted through said gears to said

70

100

105

110

115

120

125

130

4
drum. On the extreme end of the sleeve, I have also provided a beveled gear 80 which meshes with a beveled gear 81 on the hub of the disk 13. The rotation of the main shaft 5 through these gears imparts a rotation to the disk 13.

Mounted underneath the drum, and carried by the brackets 1 and 2, are guiding rails 82 and 83. Running on these guiding rails 10 is an endless conveyer 84. This endless conveyer passes over sprocket wheels 85 which are mounted on a shaft 86 journaled in the supporting bracket 1 of the machine. This shaft 86 carries a worm 15 wheel 87 which is driven by a worm gear 88 on the main shaft. The guide rails 82 and 83 are extended beyond the ends of the cylinder and are deflected upwardly and connected to the bracket 3, as clearly shown 20 in Fig. 2 of the drawings.

Rotating sprocket wheels 89 support the other end of the endless conveyer. The bracket which supports the sprocket wheels 25 may be adjusted by adjusting bolts 90 for increasing the tension on the conveyer. This conveyer consists of flat plates 91 which are joined by suitable links 92.

The closing machine A is provided with rails 93 and 94 which form a discharge 30 chute on which the closed cans roll. These rails are secured to a bracket 95 which is adjustably attached by bolts 96 to the side guide rails 82. The rail 94 projects substantially across the entire width of the conveyer, while the rail 93 extends substantially 35 half way across said conveyer. Secured to the rail 94 is a bracket 96 having a leather buffer 97 thereon. As a can rolls down the rails 93 and 94, one end thereof will be released before the other end and the can will 40 be stopped by the leather buffer 97. This causes the can to end up so as to stand upright on the conveyer. The plates 91 are of sufficient width so as to make a substantially 45 flat surface conveyer and a support for the upright cans. A guide rail 98 engages any of the cans which may be on the wrong side of the conveyer and crowds them over to the farther side of the conveyer. This leaves the front side of the 50 conveyer free for the cans discharged from the closing machine B. Said closing machine B has guide rails 99 and 100 which are attached to a bracket 101 mounted on the side guide rails 82, and a bracket 102 carries a leather buffer 103 which stops the 55 cans running along the rails 99 and 100, and these rails are so shaped that the cans will be landed up on to the conveyer. The conveyer, therefore, will collect all of the closed 60 cans from the closing machines. At the delivery end of the conveyer there is a receiving table 104. Mounted on this table and overlapping the conveyer is a deflecting plate 65 105. The table is recessed to permit

the conveyer to pass over the same with its upper face substantially flush with the upper face of the table. This deflector plate 105 strips the cans from the conveyer on to the table 104. It is obvious that in place 70 of this table other receiving means may be provided.

In the operation of our device the main shaft is set into main rotation through the shifting of the friction clutch by the hand 75 lever 64. The cans from the filling machines are delivered on to the receiving disk 13. This disk is rotated through the gear connection with the main shaft and will convey the filled cans around and deliver 80 the same one at a time and spaced from each other on to the cylinder 7. The cylinder is rotated through its gear connection with the main shaft and the thread 8 of the cylinder moves the cans along the support- 85 ing ledge against the side guiding rail.

If the gate 31 is withdrawn leaving the opening 28 free, then the can will be forced by the spiral thread on the cylinder into the opening and on to the receiving disk of the 90 closing machine A. The reciprocation of the gate 31 will help to force the can to this receiving disk. If the gate is closed, then the filled cans will pass the opening 28 and will be delivered to the closing ma- 95 chine B.

When it is desired to put the closing machine out of operation, a swinging plate 106 is thrown over so as to close the opening 28, and the gate 31 may continue to reciprocate 100 under said plate. The plate, however, will prevent filled cans from passing through the opening.

The closed cans are delivered to the guiding rails which in turn deliver the cans to 105 the conveyer underneath the cylinder and this conveyer collects the cans from the various machines, and delivers the same on to the receiving table 104.

As clearly shown in Fig. 4 of the drawings, the cylinder has two spiral threads thereon. One is indicated at *x* and the other at *y*. For one rotation of the cylinder, it will be apparent that the can indicated at the position *a* will be moved to the 110 position *b* and the can indicated at *c* will be moved to the position indicated at *d*. By using two threads and shaping the same as above noted, we are able to greatly increase the capacity of the feed cylinder. 115 For a given speed twice as many cans will be fed thereby as where a single thread is used. The threads must necessarily be spaced a slightly greater distance than the diameter of the can, and, therefore, the 120 capacity of the feed cylinder is limited. Where two threads are used, the pitch of the threads is very much greater, without spacing adjacent threads any further, and thereby the speed of the feed of the cans is 125 130

greatly increased. This is accomplished without giving to the feed cylinder an excessive speed which would cause filled cans to spill.

- 5 In Fig. 10 of the drawings, we have shown a slightly modified form of the invention wherein three closing machines are used. The feed cylinder 7 is of the same construction as above described, and this 10 feed cylinder rotates in the supporting frame, which is formed with side members 5^a and 6^a. The side rail 12 extends along the side frame 5^a in the manner above described, and forms a supporting ledge for 15 the filled cans. This side frame is formed with an opening for the closing machine, indicated at A, and with a second opening for the closing machine indicated at C. The closing machine B is placed at the 20 end of the conveyer in the manner above described. The cans are received on to a rotating receiving table and directed to the cylinder precisely in the manner described in connection with the other figures of the 25 drawings. The operating mechanism for the drum and for the sliding bar carrying the gate 31, is also the same. The reciprocating bar 34 for the gate 31 is, however, extended along the frame and slides in a 30 second bracket 36^a. This bar is provided with a second gate 31^a, which controls the opening leading to the closing machine C. The receiving table 29^a of the closing machine C is positioned precisely the 35 same as the receiving table for the closing machine A. There is also a swinging plate 106^a, which is adapted to close the opening controlled by the gate 31^a.

The purpose of this closing apparatus is 40 to provide three machines which are fed by a single conveyer cylinder, and these three machines may be all operated simultaneously, any two of the machines operated, or one alone operated. When all three machines are in action, the closing machines A and C will take the greater portion of the cans to be closed, while those which pass these two machines will be received and closed by the machine B. When two 45 machines are in operation, the other one may be idle, for repair, and by controlling the swinging gates 106 or 106^a, either of the machines A or C may be rendered idle. If both of these gates are open, then these two 55 machines will take the normal supply to the drum, and the machine B will be idle.

From the above description, it will be apparent that we have provided an apparatus for delivering filled cans to closing 60 machines, which automatically apportions the cans to the different machines. The filled cans are fed into one end of the apparatus, and are all closed and discharged from the other end thereof. As 65 these filled cans travel from one end of the

apparatus to the other, the closing ends are applied and double-seamed on to the can bodies. This permits several closing machines to be used in connection with a single filling machine and a single conveyer. 70

It is obvious that minor changes in the details of construction and the arrangement of parts, may be made without departing from the spirit of the invention, as set forth in the appended claims. 75

Having thus described our invention, what we claim as new and desire to secure by Letters Patent is:—

1. An apparatus for delivering filled cans to a plurality of closing machines including 80 a supporting ledge, a guide rail adjacent the ledge along which the cans are fed, said guide rail having an opening therein through which the cans may pass to the closing machine, a feed cylinder having a 85 thread thereon disposed so as to move the cans along the guide rail and through the opening therein, and means for closing the opening to cause the cans to pass to another closing machine. 90

2. In an apparatus for delivering filled cans to a plurality of closing machines, including a feed cylinder having a thread 95 thereon, a supporting ledge co-operating with said feed cylinder, a guide rail adjacent said ledge along which the cans are fed by said thread on the feed cylinder, said thread being so shaped as to force the filled cans against said rail, said rail having an opening therethrough at a closing machine to 100 permit the filled cans to pass to said closing machine, and a reciprocating gate for controlling said opening whereby certain only of said cans are permitted to pass through said gate. 105

3. In an apparatus for delivering filled cans to a plurality of closing machines, including a feed cylinder having a thread thereon, a supporting ledge co-operating with 110 said feed cylinder, a guide rail adjacent said ledge along which the cans are fed by said thread on the feed cylinder, said threads being so shaped as to force the filled cans against said rail, said rail having an opening therethrough at a closing machine to 115 permit the filled cans to pass to said closing machine, and a reciprocating gate for controlling said opening whereby certain only of said cans are permitted to pass through said gate, said gate having the edge thereof 120 adjacent the cylinder in line with the edge of the guide rail and the rear edge thereof inclined to assist in crowding the filled cans on to the receiving table of the closing machine. 125

4. In an apparatus for delivering filled cans to a plurality of closing machines, including a feed cylinder having a thread thereon, a supporting ledge co-operating with 130 said feed cylinder, a guide rail adjacent said

ledge along which the cans are fed by said thread on the feed cylinder, said thread being so shaped as to force the filled cans against said rail, said rail having an opening therethrough at a closing machine to permit the filled cans to pass to said closing machine, and a reciprocating gate for controlling said opening whereby certain only of said cans are permitted to pass through 5 said gate, said gate having the edge thereof adjacent the cylinder in a line with the edge of the guide rail and the rear edge thereof inclined to assist in crowding the filled cans on to the receiving table of the closing machine, and means independent of said gate 10 for closing the opening so as to prevent the cans passing therethrough when said gate is retracted.

5. An apparatus for delivering filled cans 20 to a plurality of closing machines including a supporting frame, a cylinder mounted in said frame and having a thread wound thereon projecting above the upper face of the frame whereby a filled can may rest on 25 said frame and said cylinder and be forced along the frame by said thread, a guide rail attached to said frame against which and along which the cans are moved by said thread; said guide rail having an opening 30 therethrough at a closing machine, the thread on said cylinder being disposed so as to cause the cans to be forced through the opening, and a sliding gate for controlling said opening.

35 6. An apparatus for delivering filled cans to a plurality of closing machines including a supporting frame, a cylinder mounted in said frame and having a thread wound thereon projecting above the upper face of 40 the frame whereby a filled can may rest on said frame and said cylinder and be forced along the frame by said thread, a guide rail attached to said frame against which and along which the cans are moved by said 45 thread; said guide rail having an opening therethrough at a closing machine to permit certain of the cans to be forced through the opening by the thread on said cylinder, and a sliding gate for controlling said opening, 50 said sliding gate having its edge adjacent the cylinder in line with said guide rail and its opposite edge inclined so as to crowd the cans on to the receiving table of the closing machine.

55 7. An apparatus for delivering filled cans to a plurality of closing machines including a supporting frame, a rotating cylinder mounted on said frame, said supporting frame including spaced ledges, said cylinder 60 having a thread thereon extending into the space between the ledges and projecting above the upper face thereof, a guide rail along one of said ledges, said thread being so disposed that the filled cans resting on 65 said frame and ledge may be moved along

said guide rail and forced against the same, said guide rail having an opening therethrough to permit the cans to be crowded by the thread through the rail, said ledge which supports the cans having a recess in 70 its upper face adapted to receive the table of a closing machine whereby the upper surface of the table is substantially flush with the upper surface of the ledge so that the cans may be forced on to the table, and 75 a reciprocating gate for controlling said opening.

8. An apparatus for delivering filled cans to a plurality of closing machines including a support, a guide rail along which the cans 80 are fed, said guide rail having an opening therein through which the cans are adapted to pass to a closing machine, a rotating feed cylinder having a thread thereon for moving the cans along said guide rail and through 85 said opening, means for closing said opening, and a rotating feed table for delivering the filled cans onto the feed cylinder.

9. An apparatus for delivering filled cans to a plurality of closing machines including 90 a support, a guide rail along which the cans are fed, said guide rail having an opening therein through which the cans are adapted to pass to a closing machine, a rotating feed cylinder having a thread thereon for moving 95 the cans along said guide rail and through said opening, means for closing said opening, a rotating feed table for delivering the filled cans onto the feed cylinder, and a spacing plate for spacing the filled cans 100 as they are delivered to said rotating feed cylinder.

10. An apparatus for delivering filled cans to a plurality of closing machines including a support, a guide rail along which the cans are fed, said guide rail having an opening therein through which the cans are adapted to pass to a closing machine, a rotating feed cylinder having a thread thereon for moving the cans along said guide rail 105 and through said opening, means for closing said opening, a rotating feed table for delivering the filled cans onto the feed cylinder, and a pivoted spacing plate for automatically spacing the filled cans as they are 110 delivered to the feed cylinder.

11. The combination of a plurality of closing machines, a support for the cans, a guide rail along which the cans are fed to the closing machines, said guide rail having 115 an opening therein through which the cans are adapted to pass to one of said closing machines, a rotating feed cylinder having a thread thereon for moving the cans along said guide rail and through said opening, means for closing said opening, a rotating feed table for delivering the filled cans onto the feed cylinder, a conveyor mounted beneath the feed cylinder, guiding rails for directing the closed cans from a closing ma- 120 125 130

chine to the conveyer, said guiding rails including devices for setting the cans on end on said conveyer.

12. An apparatus for delivering filled cans to a plurality of closing machines including a supporting frame, a cylinder mounted to rotate in said frame, said cylinder having a thread thereon for engaging and moving the filled cans along said frame, 5 devices coöoperating with said cylinder for apportioning and feeding the filled cans to the several closing machines, said devices including a reciprocating gate, means for rotating said cylinder, means for reciprocating said gate, in timed relation to the rotation of said cylinder, and a rotating table for receiving the filled cans and delivering the same to the feed cylinder, said table being rotated by said cylinder.
- 10 13. An apparatus for delivering filled cans to a plurality of closing machines including a support, a guide rail having an opening through which the cans may pass

to a closing machine, a feed cylinder having two threads spirally interwound thereon, the 25 distance between the threads being greater than the diameter of the cans to be conveyed, a reciprocating gate for closing said opening, said reciprocating gate being timed relative to the movements of the feed cylinder so that the cans fed by one of the threads only will be caused to pass through said opening, while the cans fed by the other thread are carried across the opening when the gates are closed. 30 35

In testimony whereof, we affix our signatures in the presence of two witnesses.

IVAR F. WARME.

JOHN C. TALIAFERRO.

Mr. Warme's witnesses:

GEORGE HARKNESS,
REYNOLD J. NITSCH.

Mr. Taliaferro's witnesses:

REGINALD KEENE,
A. B. ZIBBUTT.
